Primary Examiner—Cathron Brooks*Assistant Examiner*—Angela J Lee(74) *Attorney, Agent, or Firm*—John L. Rogitz(57) **CLAIM**

The ornamental design for the computer screen with display, as shown and described.

DESCRIPTION

FIG. 1A is a screen shot of a first embodiment of the computer screen with display, showing the upper portion of the display;

FIG. 1B is a screen shot showing the lower portion of the display of FIG. 1A;

FIG. 2A is a screen shot of a second embodiment of the computer screen with display, showing the upper portion of the display; and,

FIG. 2B is a screen shot showing the lower portion of the display of FIG. 2A.

The perimeters of the portion of the underlying computer screen and the display are understood to be flush.
